The ornamental design for a detection device for medical purposes, as shown and described.

DESCRIPTION

The file of this patent contains at least one photograph executed in color. Copies of this patent with color photographs will be provided by the Office upon request and payment of the necessary fee.

FIG. 1 is a front elevation view of a detection device for medical purposes showing my new design, the back, left and right elevation views thereof are the same of the front elevation view;

FIG. 2 is a top plan view thereof;

FIG. 3 is a bottom plan view thereof;

FIG. 4 is a top left perspective view thereof; and,

FIG. 5 is a bottom left perspective view thereof.
